(57) **CLAIM**

The ornamental design for a medical imaging device pad holder as shown and described.

DESCRIPTION

FIG. 1 is a front-right perspective view of a medical imaging device pad holder according to the claimed design.

FIG. 2 is a rear-left perspective view of the medical imaging device pad holder.

FIG. 3 is a top view of the medical imaging device pad holder.

FIG. 4 is a bottom view of the medical imaging device pad holder.

FIG. 5 is a rear view of the medical imaging device pad holder.

FIG. 6 is a front view of the medical imaging device pad holder.

FIG. 7 is a right side view of the medical imaging device pad holder.

FIG. 8 is a left side view of the medical imaging device pad holder; and,

FIG. 9 is a sectional view of the medical imaging device pad holder taken along line 9-9 in FIG. 3.

The broken lines in the drawings illustrate portions of the medical imaging device pad holder that form no part of the claimed design.
